Ivan Ročić, New York, N. Y.

Application June 28, 1943, Serial No. 110,549

Term of patent 14 years

(Cl. D91—3)

To all whom it may concern:

Be it known that I, Ivan Ročić, a citizen of Croatia, Yugoslavia, and a resident of the city of New York, county of New York, and State of New York, have invented a new, original, and ornamental Design for a Pliant Pipe Coupling Unit, of which the following is a specification, reference being had to the accompanying drawing, forming part thereof.

Figure 1 is a top plan view of a pliant pipe coupling unit showing my new design.

Figure 2 is a transverse sectional view on the line 2—2 of Figure 1.

Figure 3 is a longitudinal sectional view on the line 3—3 Figure 1; and

Figure 4 is a transverse sectional view on the line 4—4 Figure 1.

The pipe ends are shown for illustrative purpose only.

I claim:

The ornamental design for a pliant pipe coupling unit, as shown and described.

IVAN ROČIĆ.
